NOISEMAKER BUILDING BLOCK

George Jentzen, North Bergen, N. J.

Substituted for abandoned application Serial No. 496,386, July 28, 1943. This application July 7, 1945, Serial No. 603,699

2 Claims. (Cl. 46—24)

1

This invention relates to new and useful improvements in toy building blocks and is a substitute for a portion of the subject matter contained in my original application Serial No. 496,386, filed July 28, 1943.

More specifically, the present invention proposes the construction of a toy building block characterized by the fact that it is hollow and contains a noise maker so as to add to its appeal to small children.

Another object of the present invention proposes that at least one of the sides of the building block should be open in a manner to permit the noises created by the noise maker to clearly emanate from the interior of the block.

Still another object of the present invention proposes a novel arrangement for releasably closing the open side or sides of the block in a manner to retain the noise maker in position within the block and permit it to be removed and replaced by different noise makers, toy gyroscopes, humming tops and other similar articles.

A still further object of the present invention proposes making the releasable closing means for the open side or sides of the block adjustable to accommodate the same to noise makers of different sizes.

The present invention also proposes to so construct the releasable closing means so that it only closes a part of the open side or sides of the block in a manner so as not to interfere with the passage of the noise from the interior of the block.

The invention further proposes forming the building blocks of any desired shape or size and of cardboard, paper, fiber, resinous plastic materials, metals, glass or other similar materials and providing the outer faces of the side walls of the block with pictures, letters of the alphabet or other attractive designs having an appeal to children.

It is a further object of the present invention to construct a building block which is simple and durable and which can be manufactured and offered for sale at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a building block constructed in accordance with the present invention.

Fig. 2 is a plan view of Fig. 1.

Fig. 3 is an enlarged detailed view of a portion of Fig. 1 having the cord broken away to reveal underneath constructions.

2

Fig. 4 is a partial vertical sectional view taken on the line 4—4 of Fig. 2.

Fig. 5 is a sectional view taken substantially on the line 5—5 of Fig. 3.

Fig. 6 is a perspective view of one of the pins shown per se.

The toy building block, according to the present invention, includes a hollow block body 10 having the usual side walls 11 and with its top and bottom open. The block body is shown as being in the form of a cube, but this is by way of illustration only as it may be of any desired shape or size. The block body 10 is formed of cardboard, heavy paper, fiber, resinous plastic material, metal, glass or any other similar material and the outer faces of the side walls may be imprinted with pictures of animals, letters of the alphabet or other attractive designs (not shown), as is generally known in the art to which the present invention pertains, having an appeal to small children.

Disposed within the hollow of the block body 10, there is a noise maker 12 for making a noise which will emanate from the open top and bottom of the block body 10 and so add to the appeal which the block will have to children. For the purpose of illustration, the noise maker 12 is shown as being in the form of a bell having a swinging clapper 13 to make a ringing noise when the block is handled. However, the illustration of the noise maker in the form of a bell is not to be considered as limiting, as other forms of noise makers or similar devices may be substituted for the bell.

Means is provided for partially closing the open top and bottom of the block body to releasably retain the noise maker 12 in position within the block body 10 so that it can be removed and replaced by other forms of noise makers or similar devices when desired. The closing means is adjustable so that it may be adjusted to accommodate noise makers of different sizes.

The holding means is characterized by slots 14 extended inwards from the edges of the side walls 11 at the open top and bottom of the block body 10. The slots 14 are provided with opposed aligned pairs of cutouts 15 along the lengths thereof. Pins 16 have pointed shank portions 17 pressed into the material of the side walls 11 at the bases of the slots 14, see especially Fig. 4. The outer ends of the pointed shank portions 17 of the pins 16 are formed with transverse heads 18 selectively engageable with a desired aligned pair of the cutouts 15, as clearly shown in Figs. 3 and 4.

Cords 19 are extended about the block body 10 and across the heads 28 within the slots 14 and have their free ends tied into knots 20 for releasably holding the noise maker 12 in position 60 within the block body 10 without interfering

with the passage of the noise from the open top and bottom of the block body.

With this arrangement, when the cords 19 are removed, it is possible to turn the pins 16 about their inserted pointed shank portions 17 to disengage the heads 18 from the cutouts 15 of the slots 14 with which they are engaged. This action will free the pins 16 to be pulled out or pushed in to align the heads with any other desired pairs of aligned cutouts 15 after which the pins 16 may again be turned about the inserted pointed shank portions 17 to frictionally reengage the heads 18 with the cutouts 15 with which the heads are now aligned. When the cords 19 are now reengaged in position, the space between the parts of the cords which extend across the open top and bottom of the block body will be increased or decreased, depending on whether the pins 16 were pushed in or pulled out, to agree with the height of the particular noise maker inserted into the hollow of the block body.

While I have illustrated and described the preferred embodiment of my invention, it is to be understood that I do not limit myself to the precise constrictions herein disclosed and the right is reserved to all changes and modifications coming within the scope of the invention as defined in the appended claims.

Having thus described my invention, what I claim as new, and desire to secure by United States Letters Patent is:

1. A hollow toy building block having an open side with a noise-maker in said block, cords tied around said block and engaging the ends of said noise-maker holding it in position in said block, said block being formed with slots in its side walls through which said cords pass, and means for holding said cords in various adjusted posi-

tions in said slots, comprising pins having their pointed ends extended into the material of the side walls of said block at the base of said slots, said slots being formed with aligned cutouts on opposite sides thereof, and heads formed on said pins and against which said cords engage and selectively engageable with said cutouts for holding said pins in adjusted positions in said slots.

2. In a toy building block having a hollow block body formed with side walls and an open top and bottom and containing a noise maker, the side walls being formed with slots extended inward from the top and bottom edges thereof, the material of the side walls along opposite sides of said slots being formed with aligned pairs of cutouts, pins having pointed shank portions pressed into the material of the side walls at the bases of said slots and head portions on the outer ends of said shank portions and selectively engageable with the cutouts of said slots to space said head portions at the top and bottom of the block body a distance equal to the height of the contained noise maker, and cords engaged about the block body and through the outer ends of said slots to engage said head portions to be held with their portions which extend across the open top and bottom of the block body in engagement with the top and bottom of the noise maker and retain it in position within the block body.

GEORGE JENTZEN.
